(57) **CLAIM**

The ornamental design for a toilet brush holder, as shown and described.

DESCRIPTION

FIG. 1 is a front perspective view of a toilet brush holder, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a perspective view of the toilet brush holder of FIG. 1 wherein a drawer of the toilet brush holder is opened. The dashed lines immediately adjacent to the shaded areas in the figures represent the boundaries of the claimed design. The dashed lines in the figures illustrate the portions of the design that form no part of the claimed design. None of the broken lines form any part of the claimed design.
